UNITED STATES PATENT OFFICE.

JOSEPH WHITE, OF BOUNDBROOK, NEW JERSEY, ASSIGNOR TO THE
ALUMINUM PRESS, OF NEW YORK, N. Y., A CORPORATION OF NEW
YORK.

TRIP-MOTION FOR PRINTING-MACHINES.

No. 833,276.

Specification of Letters Patent.

Patented Oct. 16, 1906.

Application filed October 6, 1905. Serial No. 281,708.

To all whom it may concern:

Be it known that I, JOSEPH WHITE, a citizen of the United States, residing at Boundbrook, county of Somerset, State of New Jersey, have invented certain new and useful Improvements Relating to a Trip-Motion for Printing-Machines, fully described and represented in the following specification and accompanying drawings.

The machine illustrated, in which the improvements embodying this invention are incorporated, is a rotary multicolor lithographic machine, and while the principles of the invention are more particularly adapted to this type they are not limited to the same and apply as well to a single-color rotary or in some of its features to a machine in which the form is attached to a reciprocating bed and coacts with an impression-cylinder.

Referring to the drawings, Figure 1 is an elevation of a two-color rotary lithographic printing-machine, the front frame and cylinders being removed to more clearly show the mechanism situated between the printing-cylinders and the rear frame as the mechanism between the cylinders and the frame embody this invention. Fig. 2 is an enlarged view of one of the trip-levers. Fig. 3 is another view of the same, taken in the direction of the arrow 3 of Fig. 2.

Referring to Fig. 1, 1 is a partly-diagrammatical representation of the impression-cylinder of the machine, said impression-cylinder making one revolution to each sheet printed, said sheets being fed from the feed-board 20 and being taken by the grippers 6, which are actuated by any usual gripper mechanism.

2 and 3 represent the form-cylinders of this machine, which are one-half the diameter of the impression-cylinder, therefore makes two revolutions to each one of the impression-cylinder. These have the planographic forms of suitable material, (usually aluminium or zinc,) which in normal printing relation apply their ink designs to the sheets of paper fed between the impression-cylinder and the design-cylinder, the ink being supplied to the forms by the set of rollers 5, 5, diagrammatically shown above the form-cylinders.

In normal printing operation the form-cylinders are placed in printing relation with the impression-cylinders, and at the proper time

when the impression-surface comes in contact with the form-surface the sheet is printed upon. 55

The impression-cylinder 1 and the plate-cylinders 2 and 3 rotate in unison by means of gears whose pitch-diameter corresponds with the printing-surfaces, said cylinder-gears being attached to the shafts of their respective cylinders in the usual manner, and therefore not illustrated, the source of driving being obtained from the pinion 10. (Shown 60 diagrammatically.)

During the normal printing operation the printing-cylinders remain in fixed diametral relation to each other, and the sheet being fed to the impression-cylinders receives the 65 design from the plate-cylinder 2 and then on its forward movement receives the design from the plate-cylinder 3 and is delivered by any form of delivery mechanism. (Not shown.) 70

For various reasons—as, for instance, when a sheet is missed by the feeder or on starting up the machine when it is desirous to first ink up the forms before the printing operation begins—it is necessary to separate the 75 cylinders, thereby placing them out of printing relation with each other. This may be accomplished by mounting either the impression member or the form members in movable bearings; but in the construction 80 shown preferably the plate-cylinders are moved, although (by a modification of the same mechanism embodied in this invention) it could be arranged to move the impression-cylinder instead; but, as shown, the impression-cylinder 1 is mounted in a fixed bearing 85 formed by the side frame 8 and side frame cap 9, and the plate-cylinders are mounted in eccentric-bearings 10 and 11, which when rocked cause the plate-cylinders to change 90 their diametral relation to the impression-cylinder, moving them to and from the impression-cylinder. These eccentric-bearings receive their motion through the agency (in 95 a manner to be described) of pivoted members which are engaged at one end by a rotating member, in this case a cam on the impression-cylinder. This pivoted member is engaged on one side of the pivot to move the cylinder in one direction and on the other 100 side of its pivot to move the cylinder in the other direction, and while the medium of bringing these opposite ends into engage- 105

ment with (in this case) the rotating cam is a sliding stud the principle is not necessarily limited to the mechanism shown, as it can be readily seen that various methods 5 widely differing from this for the purpose of bringing either end of the pivoted member into engagement with the rotating part could readily be devised by a skilled designer acquainted with the principle.

10 Pivots mounted inside of each of the front and rear frames 8 and adjacent to the impression-cylinder 1 are two pairs of trip-levers 12 and 13, (one pair for each plate-cylinder,) which levers are connected to the eccentric-boxes through the following means: 15 Each lever has formed on it a forked arm 14, which holds the pins 15, to which is pivoted the connection 16 and 17, the other end of which is pivoted to the eyes 27 and 28, which 20 are fastened to the eccentric-boxes 10 and 11. When the trip-levers 12 and 13 are rocked, (through agencies to be described,) the eccentric-boxes 10 and 11 are moved so as to move the plate-cylinders to and from the 25 impression-cylinder. The trip-levers have hubs 18 and 19, which contain sliding bolts 20 and 21, upon which are the antifriction-rollers 22 and 23. These bolts are so governed that at the proper time the proper ones 30 are placed in the path of the trip-cams 24, which are bolted to the impression-cylinder ends and rotate with it.

It can be seen by referring to Fig. 1 that 35 the cam 24 in revolving has just come adjacent to one of the rollers 23 of trip-lever 13 and will in its forward movement press said roller toward the impression-cylinder shaft and in doing so will rock lever 13, thereby moving connection 17 and rocking the eccentric-boxes 11 in the direction of the arrow 40 and in doing so the eccentric being so arranged will bring the plate-cylinder 3 into printing relation with the impression-cylinder 1. The trip-lever 12 has just previously 45 (as can be seen by observing Fig. 1) been subjected to the movement described, and the plate-cylinder 2 is shown in printing relation and the plate-cylinder 3 is just about to go into printing relation with the impression-cylinder 1, and as long as both plate-cylinders remain in printing relation with the impression-cylinder the printing operation is 50 continuous, the three cylinders keeping their relative diametral positions, and at each revolution of the impression-cylinder it takes the sheet from the feed-board, brings this sheet into printing relation with the form on the first plate-cylinder 2 and then with the form on the second plate-cylinder 3, and then 55 60 delivers it to the delivery mechanism. When it is desirous—as, for instance, when a sheet is missed—to interrupt this printing action, the roller 22 and the sliding bolt 20, which is seated in the hub 19, formed on the 65 trip-lever, are moved into the path of the cam

24 on the impression-cylinder 1, and they are caused to rock in a direction opposite to which they were rocked when the rollers 23 were placed in engagement. This causes the eccentric-boxes 10 and 11 (by means of the 70 connections 16 and 17 and eyepieces 27 and 28) to be rocked so as to remove the plate-cylinders out of printing relation with the impression-cylinder, where they will remain until the sliding bolts in the trip-levers are 75 again actuated. It can be seen that while the rollers 23 when rocked toward the impression-cylinder shaft are still in the same plane laterally with their actuating-cams they have been pushed forward by the cam 80 over the highest part of the same and are out of the path of its movement in that direction, whereas the other end of the trip-levers have now been rocked toward the periphery of the plate-cylinder adjacent to the path of the 85 cam; but as the rollers 23 are withdrawn into their hubs they are not moved by the cams 24. When it is desirous to again move the plate-cylinders, these studs are placed in the path of the cam by sliding them in their 90 hubs, so as to cause them to project within the path of the cams. The manner in which these studs are actuated may be varied widely; but this preferably is accomplished by the means illustrated.

95 The trip-levers 12 and 13 are centered on the hubs 28, upon which are pivotally mounted at 29 the actuating-levers 30, which perform the function of moving the cam-rollers and studs into and out of the path of the 10 cam and at the same time locks the proper roller and stud in operative position in relation to the cam in the following manner: One end of this actuating-lever 30 engages a pin 31 in the stud 21 and the opposite end of the pin 32 in the stud 20. These pins 31 and 32 are guided in slots 33 and 34, and when the fork formed on the ends of lever 30 engages the pin this pin will be moved outward in the straight part of the slots formed in the hubs 11 18 and 19 until it reaches the curved portion, where it will turn in this curve and allow the face 35 to come under it, as is shown with pin 32, Fig. 3. Now it can be seen that any pressure exerted on the roller 22 tending to move 110 it inward will cause the pin 32 to crowd against the face 35, which will prevent the movement of the stud 20, thus forming an effective lock. When the actuating-lever 30 is moved in an opposite direction, the same 115 operation occurs with relation to the stud 21 and rollers 23 at the opposite end of the trip-lever. The spring 36 works across its center 37 when the lever is moved, thereby holding it in the position in which it is placed. The 120 manner in which this actuating-lever 30 may be controlled by the operator may be varied widely; but the preferable form is shown.

125 When the operator desires to bring the press into printing relation, (assuming it to 130

be in tripped position,) he presses on the treadle 38 and brings the pin 39 under the catch 40 and through the medium of the connection 41, lever 42, shaft 43, (which reaches 5 across the machine and finds its bearing in the front and rear frames,) and connection 44, extending upward from the levers 45 on both sides of the machine, operates the actuating-plates 46. These plates have slots 47, which 10 engage the pins 48 on the levers 30, rocking them in the desired direction. These actuating-plates 46 and 56 are preferably centered on the studs 49, which are screwed in the center of the stud 50, upon which the 15 trip-levers are pivoted. In the case of a multicolor-machine, as is illustrated, these actuating-plates 46 have pivoted upon them the connections 60, which are pivoted at the other end to the actuating-plates 56, thereby 20 causing both sets of actuating-plates to operate together to move the sliding studs to produce the effect desired. The studs 23 (as in Fig. 1) having been moved in the path of the 25 cams 24 are engaged by the cams, rocking the studs and lever toward the cylinder-shaft, and as the actuating-plates 46 and 56 have been kept stationary the pins 48 upon the actuating-levers have moved forward in the 30 slots 47. This position is shown with relation to the first trip-lever 12. The second trip-lever is about to be rocked, as described.

When it is desired to trip the cylinders out of printing relation with each other, the treadle 38 is kicked, releasing the pin 39 from 35 the latch 40, allowing the spring 52 to cause the actuating-lever and mechanism to move in the opposite direction, throwing the opposite studs in the path of the cams 24 and locking them there, so that on the next revolution 40 of the impression-cylinder the plate-cylinders will be rocked out of printing relation with the impression-cylinder.

Although the actuating-plates are shown directly connected to the foot-treadle mechanism, a timing mechanism may be interposed between the foot and actuating mechanisms whereby the trip-lever bolts may be automatically actuated upon at a predetermined time in the sequence of the printing, 45 so as to prevent these sliding bolts from being moved at a time that may cause damage—as, for instance, when the bolts to be moved outward are opposite the face of the cam.

It has been found that when under printing pressure an eccentric-bearing tends to rotate with the cylinder-journal, thus displacing the cylinder, and for this purpose where 55 an eccentric-box is used it has been customary to provide locking mechanisms more or less complicated—as, for instance, the one shown in the United States application, No. 277,257, applied for by Thomas G. Claridge and Thomas A. Randall, September 6, 1905; but I have found that by arranging the centers so that when the eccentric-

bearing is rotated to throw the cylinder in impression in the same direction as the cylinder rotates it is only necessary to provide a stop to limit the movement of the eccentric-bearing. For this purpose I have provided 70 pins 53, against which the arms 14 are moved when the parts are brought into printing position, and when the printing pressure is taken by the bearing these arms 14 are crowded against the pins, firmly locking the cylinders in printing position without additional locking mechanism.

When the trip-levers are rocked in the opposite direction away from the levers 53 and the cylinders are placed out of printing relation, there is no printing pressure. Consequently no locking mechanism is required, the friction of said eccentric-box in its bearing being sufficient to keep it in place when 80 no pressure is on it.

Cams 24 are bolted in a fixed position to the impression-cylinder ends and are formed, as shown, with a double cam-surface, so that if the trip-lever studs are thrown into the path of the cams these cams will properly engage the studs whether the cylinder is moved forward or backward, thus avoiding breakage.

I claim—

1. In a printing-machine, cylinder-moving 95 means having a pivoted lever having two arms containing sliding bolts, a rotating cam, means for moving one of said bolts into the path of the cam to rock the lever to place the printing members out of printing relation, 100 and the other of said bolts into the path of said cam to place the printing members into printing relation.

2. The combination of an impression-cylinder and a form-cylinder, a cam rotating 105 with one of said cylinders, a pivoted lever having two arms, means for causing the cam to engage the lever at one arm to rock said lever to place the cylinders into printing relation, and at the other arm to place the cylinders out of printing relation.

3. The combination of an impression-cylinder and a form-cylinder, a cam rotating in a fixed relation with one of said cylinders, a pivoted lever having two arms containing 115 sliding bolts, means for moving one of said bolts into the path of the cam, thereby causing said cam to rock said lever to place the printing-cylinders out of printing relation and the other of said bolts into the path of 120 said cam to place the cylinders into printing relation.

4. The combination of an impression-cylinder mounted in fixed bearings and a form-cylinder mounted in eccentric-bearings, a cam 125 rotating in fixed relation with the impression-cylinder, a pivoted lever mounted on the frame adjacent to the impression-cylinder, connections between the lever and the eccentric-bearings, means for causing said cam to 130

engage the pivoted lever on one side of its pivot to rock said eccentric-bearing to separate the cylinders, and to engage said pivoted lever on the other side of its pivot to 60
5 rock the eccentric-bearing to place the cylinders in printing relation.

5. The combination of an impression-cylinder mounted in fixed bearings and a plurality of form-cylinders mounted in eccentric-bearings, a cam rotating in fixed relation with the impression-cylinders, pivoted levers mounted on the frame adjacent to the impression-cylinder, connections between the levers and the eccentric-bearings of said form-cylinders, means for causing said cam to engage the pivoted levers on one side of its pivot to rock said eccentric-bearings to separate the cylinders and to engage said pivoted levers on the other side of its pivot to rock the eccentric-bearings to place the cylinders in printing relation. 70
10
15
20
25

6. In a printing-machine, cylinder-moving means having a pivoted member and rotating cam; said pivoted member having two engaging bolts, means for moving one of said bolts into the plane of said cam when the other bolt is moved out of the plane of said cam, said cam engaging one bolt to rock said member to place the cylinders in printing relation, and engaging the other bolt to place the cylinders out of printing relation. 80
30
35

7. In a printing-machine, cylinder-moving means having a pivoted member and rotating cam; said pivoted member having two engaging bolts and a lever pivoted on said member to move one bolt into the plane of the said cam when the other bolt is moved by said lever out of the plane of said cam, said cam engaging one bolt to place the cylinders in printing relation and engaging the other bolt to place the cylinders out of printing relation. 90
40
45

8. In a printing-machine, cylinder-moving means having a pivoted member and rotating cam, said pivoted member having two engaging bolts, a lever mounted on said pivoted member to move said bolts in opposite directions, said lever locking one of the bolts in operative relation with said cam. 100
45

50
55 9. In a printing-machine, a cam rotating with a printing-cylinder, a pivoted member adjacent to said cylinder containing two sliding bolts, a lever mounted on said pivoted member to move the sliding bolts, an actuating part centered on the pivoted member's center engaging the bolt-moving lever to

move the sliding bolts in opposite directions, said sliding bolts being engaged by the cam to move the pivoted member to separate the printing members. 60

10. In a printing-machine, a cam rotating with a printing-cylinder, a pivoted member adjacent to said cylinder containing two sliding bolts, a lever mounted on said pivoted member to move the sliding bolts, an actuating part centered on the pivoted member's center, engaging the bolt-moving lever to move the sliding bolts in opposite directions and locking one of the bolts when in the path of the rotating cam, said cam engaging the bolts to rock the pivoted member to separate the printing members. 65
70

11. In a printing-machine having a form-cylinder and impression-cylinder, one of said cylinders being mounted in eccentric-bearings for the purpose of placing the cylinders into and out of printing relation to each other; a stop for preventing the rotation of the eccentric-bearing by the printing pressure; said eccentric-bearing being rotated in the same direction as the cylinder to place the cylinders into printing relation. 75
80

12. In a printing-machine having a plurality of form-cylinders and an impression-cylinder, said impression-cylinder being mounted in stationary bearings and the form-cylinder in eccentric-bearing for the purpose of moving the form-cylinders into and out of printing relation to each other, and stops for preventing the rotation of the eccentric-bearings by 90
95 the printing pressure. 85

13. The combination of an impression-cylinder mounted in fixed bearings and a form-cylinder mounted in eccentric-bearings, a cam rotating with the impression-cylinder, a pivoted lever mounted on the frame adjacent to the impression-cylinder, connections between the lever and eccentric-bearing, a stop for preventing the movement of the parts by the printing pressure, said cam engaging the pivoted lever to rock the eccentric-bearing in the same direction that the plate-cylinder rotates, thereby bringing the form-cylinder into printing relation with one of the moving parts against the stop. 100
95
105

In witness whereof I have hereunto set my hand in the presence of two subscribing witnesses.
